UNITED STATES PATENT OFFICE

JOHN L. REMLINGER, OF PROVIDENCE, ASSIGNOR TO WILLIAM A. BEATTY,
OF PAWTUCKET, RHODE ISLAND.

DESIGN FOR A SCARF-PIN.

Specification forming part of Design No. 11,359, dated August 19, 1879; application filed June 30, 1879.
[Term of patent 3½ years.]

To all whom it may concern:

Be it known that I, JOHN L. REMLINGER, of Providence, in the county of Providence and State of Rhode Island, have originated a new Design in the Manufacture of Jewelry and other similar articles, of which the following is a full, clear, and exact description, reference being had to the accompanying drawing, which is hereby made part of this specification.

My said design relates to an improved pattern for a scarf-pin and other similar articles; and consists of three projecting arms from the upper end of the pins, two of which said arms support a mirror, and the other of said arms supports the figure of a monkey in a sitting posture gazing into a mirror, and at such angle relative to the mirror that his figure will be reflected therefrom.

In the accompanying drawing, *a* represents the pin; *c*, the mirror supported by the arms aforesaid; and *e* shows the sitting figure of the monkey resting upon the arm *i*, and extending his foot under the mirror and between

the two arms, by which it is supported as aforesaid.

The face of the mirror may be of metal or of glass; but it is my purpose to make them of polished nickel or other light-colored metal, with a golden or gilded frame, as indicated in said drawing.

The design should be worked out in suitable colors to produce a natural and pleasing effect.

I claim as my invention and desire to secure by Letters Patent—

The design for a scarf-pin and other articles of jewelry and ornament, representing the figure of a monkey placed before a mirror, and at such angle relative thereto that the figure will be reflected in and from the mirror aforesaid, substantially as shown in the accompanying illustration.

JOHN L. REMLINGER.
